UNITED STATES PATENT OFFICE

2,087,905

FUSE

Alvin L. French, Chicago, Ill., assignor to Perma Fuse Co., Chicago, Ill., a corporation of Illinois

Application December 7, 1935, Serial No. 53,319

8 Claims. (Cl. 200—113)

The present invention is primarily concerned with an improved fuse construction and more particularly with improvements in fuses of the type utilizing a capillary thread of liquid conductor such as mercury, which upon flow of excessive current, will interrupt a circuit therethrough, but which may be reset for further use, simply by moving the fuse with a snap action of the wrist.

A further object of the invention resides in improvements in the construction of fuses of the herein described type which will enable such fuses to be more easily and less expensively manufactured, yet will at all times operate efficiently and reliably.

15 It is also an important object of the invention to provide a novel cartridge unit within which the operative parts of the fuse are enclosed, this cartridge being adapted for assembly with other parts by means of which it may be readily connected and disconnected relative to the circuit to be protected.

Still another object of the invention is to provide a fuse of the herein disclosed type having improved circuit interrupting characteristics, whereby an arc extinguishing medium will be exuded from the walls of the capillary tube under the action of the arc.

In accordance with the general features of the invention, it is proposed to provide a cartridge assembly composed of a tube of insulating material having a longitudinally extending bore of capillary caliber. This tube is reinforced at its end portions by cap members forming electrical contacts. One of these cap members is extended 30 to form an expansion chamber and also provide radiating surface for the dissipation of heat generated during the interruption of current in the device. Abutting the tube and disposed within this chamber is a metal disk having a central bore arranged to register with the bore of the tube. This disk is secured in position by virtue of a press fit contact at its periphery with the interior wall of the expansion chamber. The tube and bore of the metal disk are arranged to be 35 filled with a liquid conductor such as mercury which is adapted to vaporize when a predetermined current flows through the thread of liquid within the tube. This vaporization causes the mercury to be forced out in vapor form into the expansion chamber where its contact with the interior wall thereof will cause it to condense. In this connection, the efficiency of the cartridge is also increased by virtue of constructing the tube of a material which under the action of the 40 electrical arc when the circuit is broken has the

characteristic of exuding a medium which operates to extinguish the arc.

An additional feature of the invention resides in the manner of adapting the cartridge for connection and disconnection into a circuit to be 5 protected. In the novel construction disclosed on the drawings, a screw ferrule having inwardly projecting flexible tongues is provided. These tongues are spaced apart at their free ends so as to permit sliding the ferrule axially over the 10 cartridge with the tongues in engagement with the elongated cap forming the expansion chamber. These tongues also function to maintain the ferrule in symmetrically spaced position relative to the cartridge and enable a body of non-conducting moldable material to be compressed around the cartridge and within the ferrule so as to form a rigid fuse plug having the outer surface of the ferrule and the other contacts exposed.

Other objects and features of the invention 20 will more fully appear from the following detailed description, taken in connection with the accompanying drawing, which illustrates several embodiments thereof, and in which:

Figure 1 is a view in elevation of a fuse plug 25 embodying the features of the present invention;

Figure 2 is a similar view showing a modified body construction;

Figure 3 is an enlarged sectional view through the fuse plug, the cartridge being shown in elevation, taken substantially on line III—III of 30 Figure 1;

Figure 4 is a transverse section through the fuse plug to show the cooperative engagement between the tongues of the ferrule and the cartridge, taken substantially on line IV—IV of 35 Figure 3; and

Figure 5 is an enlarged vertical sectional view taken through the cartridge assembly of the plug showing the details of its construction.

As shown on the drawing:

Figures 1 and 2 of the drawing disclose a preferred and modified form of a fuse plug embodying the present invention. The internal construction of the preferred and modified forms is 45 identical, the only difference being in the external construction of the body of the plug. In Figure 1, the portion of the body which is arranged to be grasped when inserting the plug in a proper adapter, is circular in form, whereas in the embodiment shown in Figure 2, this portion of the plug is made polygonal so that greater pressure may be applied while screwing the plug into and out of a receptacle. Moreover if necessary, this form of body enables a wrench or other tool to 50 55

be applied to the body whereby still greater force may be utilized to remove the plug from its adapter.

- Internally, the plug comprises a cartridge, generally indicated at 10 which is assembled to form a unitary structure and embody the operative parts for interrupting the flow of current in a circuit to be protected, when this current reaches a predetermined high value.
- 10 The cartridge comprises a tube 11 having a longitudinally extending bore 12 of capillary caliber. This bore extends from one end of the tube to the other and is arranged to be filled with a liquid conductor such as mercury, as indicated 15 at 13.

The tube is preferably constructed of a material which will under the influence of an electrical arc exude an arc extinguishing medium. For this purpose, it has been found that a tube constructed of fibrous material will have this property.

Intermediate the ends of the tube, the tube is provided with a circumferentially extending groove 14 which is utilized in securing the contact members 15 and 16 to the tube.

The contact member 15 is in the form of a cap which surrounds one end of the tube and acts as a closure member which is in contact with the mercury in the bore of the tube. The end of the 30 tube associated with the cap 15 is provided with an end contracted portion 17 which defines an abutment shoulder 18, this shoulder cooperating with one of the walls of groove 14 to form a circumferentially extending bead 19 which is inwardly disposed from the end of the tube.

The cap 15 closely and tightly surrounds this end of the tube and has its marginal rim portion 20 deflected into the groove 14 in abutting engagement with one wall of the groove. This 40 cap forms one of the contacts of the fuse and also acts to strengthen this end of the tube.

The cap 16 is in the form of an elongated cup, and the open end of this cup extends over the other end of the tube and is secured in like manner, that is, the rim margin of the cup is inwardly deflected as shown at 21 to abut the other wall of the groove 14 and retain the cup against removal from the tube.

The cap 16 extends outwardly of the associated end of the tube and defines an expansion chamber 22. Within this chamber is a metallic disk 23 having its periphery in press fit engagement with the interior wall of the expansion chamber. This disk abuts the end of the tube 55 disposed in the chamber and is provided with a central bore 24 which is in registration with the capillary bore 12 of the tube.

The ends of the disk 23 and tube 11, which face the expansion chamber, are conically recessed as shown at 25 and 26 respectively.

With the construction just described, when an excessive current flows between the contacts at the ends of the tube, the liquid conductor within the capillary bore will become vaporized and 65 set up a pressure which forces the mercury or other liquid conductor outwardly into the expansion chamber 22, thereby breaking the circuit between the contacts. The vaporized mercury, of course, due to interrupting the electric arc 70 becomes heated and its engagement with the wall of the expansion chamber causes the mercury to condense. Since a large radiating surface is provided in the cap 16, the heat from the mercury will be readily dissipated into the surrounding medium. In order to reset the fuse so that

it may again carry current, the fuse containing the cartridge is moved with a snap action of the wrist, which causes the mercury to re-establish a thread between the contacts.

The recessed portion 25 facilitates the movement of mercury from the expansion chamber into the tube, and also during the time when the mercury is forced into the expansion chamber from the tube, the recessed portion tends to act as a nozzle and enable the mercury vapor to 10 be thrown into a greater area of contact with the wall of the expansion chamber, whereby the mercury is cooled more rapidly.

The recessed portion 26 at the upper end of the tube tends to create a back pressure which 15 enables mounting of the cartridge in horizontal or other position without causing the mercury to run from the capillary tube into the expansion chamber, which would render the fuse inoperative.

The unitary cartridge assembly is susceptible of being mounted in various types of arrangements which will permit the fuse to be connected and disconnected in a circuit to be protected. For 20 purposes of illustration, I have chosen to show this cartridge mounted in a fuse of the plug type. This fuse contains a screw ferrule 27 of the usual type. In the construction of the fuse of this invention, the ferrule 27 is provided at its upper edge with a plurality, in this case four, inwardly 30 extending arms 28 which are flexible and formed at their inner ends to engage the outermost surface of the cap 16.

In the manufacture of this fuse, the ferrule is inserted over the cartridge and the arms 28 resiliently engage the outer surface of the cap 16 and also serve to initially maintain the ferrule in proper spaced relation during the molding of the fuse body 29 which will operate to 40 firmly secure the ferrule and cartridge in assembled relation.

The fuse body 29 is of a moldable insulating material such as rubber or porcelain. When the body has been molded, the parts are rigidly held in assembled position and the exterior of the ferrule as well as the lowermost end of the cap 16 45 are exposed to permit electrical connections with the usual screw type sockets.

From the foregoing description, it will be apparent that this invention provides an improved 50 fuse construction embodying a novel cartridge which may be incorporated with adapter parts by means of which it may be easily connected and disconnected relative to a circuit to be protected; an improved fuse of the type utilizing a capillary 55 tube containing a liquid conductor which is vaporized upon the flow of excessive current to open the circuit therethrough; and which utilizes a ferrule of such construction that it is initially held in proper position relative to the cartridge 60 during the molding of the body portion of the fuse plug, and in which the body thereafter rigidly holds the ferrule and cartridge in assembled position. Extinguishment of the arc is augmented by providing a tube of such material that under the action of the arc, an arc extinguishing medium is exuded. Moreover, the invention provides a fuse of the type which may be reset for using again simply by moving the fuse with a snap action of the wrist.

Now, it is of course to be understood that although I have described in detail several embodiments of the invention, the invention is not to be thus limited, but only insofar as defined by the scope and spirit of the appended claims.

I claim as my invention:

1. A current interrupter comprising a capillary tube of insulating material having an axially extending bore, a liquid conductor normally filling said bore, and a pair of terminals electrically connected by the liquid conductor in said bore, said bore being of such caliber that the liquid conductor will vaporize at a predetermined current load, and said terminals forming reinforcing casings around said tube substantially throughout its length.
2. A fuse of the character described comprising a tubular cartridge of insulating material, metallic contacts insulated relative to each other and respectively disposed at the ends of said cartridge, a metallic ferrule surrounding said cartridge and outwardly spaced relative thereto, inwardly projecting tongues carried by said ferrule for engaging one of said contacts, a body of insulating material securing said cartridge and ferrule in assembled relation, and means within said cartridge normally connecting said contacts and operative upon the flow of excessive current to disconnect said contacts relative to each other.
3. In a fuse construction, a cylindrical cartridge containing circuit interrupting means, electrically insulated contact members on said cartridge, a metal ferrule assembled to surround said cartridge, inwardly extending tongues on said ferrule resiliently engaging one of said contacts and initially spacing said ferrule symmetrically relative to said cartridge, and a body of non-conducting moldable material rigidly securing the ferrule and cartridge in assembled relation with the outer surface of the ferrule and the other contact exposed.
4. A fuse including a unitary cartridge assembly comprising a tubular member of insulating material having a capillary bore and a circumferential groove disposed in its outer surface between its ends, a metallic cap tightly fitting over one end of the tube and having its edge inwardly deflected to engage one wall of said groove, an elongated metallic cup having its rim margin surrounding the other end of said tube and its edge inwardly deflected to engage the other wall of said groove, said cup extending beyond the associated end of the tube to form a chamber, a metal disc in the chamber having a press fit engagement with the inner wall of said cup and abutting the adjacent end of the tube, a passageway in said disc interconnecting said bore and chamber, and a liquid conductor in said bore completing an electrical circuit between said cap and cup.
5. A fuse cartridge comprising a tubular member of insulating material having a longitudinal bore of capillary caliber and circumferential groove on its outer surface, a liquid conductor normally filling said bore, metal cap members respectively extending over the ends of said tube and in electrical circuit with said liquid, one of said cap members being extended outwardly of its associated tube end to define an expansion chamber, and inwardly deflected portions of said cap members disposed in said groove, whereby said cap members are retained against removal from said tube.
6. A fuse comprising a tubular member of insulating material having a circumferentially extending groove on its outer surface, metal cap members respectively extending over the ends of said tube and having their confronting ends deflected into said groove, said deflected ends being spaced apart, a non-conducting moldable material disposed in said groove between the deflected ends of said caps, and means in said tube normally connecting said caps and operative upon the flow of excessive current to disconnect said caps relative to each other.
7. A fuse comprising a tubular member of insulating material having a circumferentially extending groove on its outer surface, metal cap members respectively extending over the ends of said tube and having their confronting ends deflected into said groove, said deflected ends being spaced apart, a non-conducting moldable material surrounding the deflected end portions of said caps and filling the space in said groove between said deflected ends, and means within said tube normally connecting said caps and operative upon the flow of a predetermined current to disconnect said caps relative to each other.
8. A fuse of the character described comprising a tubular cartridge of insulating material, metallic contacts insulated relative to each other and respectively disposed at the ends of said cartridge, a metallic ferrule surrounding said cartridge and outwardly spaced relative thereto, means electrically connecting said ferrule and one of said contacts, said means serving to initially space said ferrule relative to said cartridge, and a body of moldable insulating material rigidly securing the ferrule, cartridge and means in assembled relation with the outer surface of the ferrule and the other contact exposed.

ALVIN L. FRENCH.
